UNITED STATES PATENT OFFICE.

AUGUST C. RADER, OF UPPER MONTCLAIR, NEW JERSEY.

CURTAIN-FIXTURE.

1,113,689.

Specification of Letters Patent. Patented Oct. 13, 1914.

Application filed January 5, 1914. Serial No. 810,438.

To all whom it may concern:

Be it known that I, AUGUST C. RADER, a citizen of the United States, residing at Upper Montclair, in the county of Essex and State of New Jersey, have invented a new and useful Curtain-Fixture, of which the following is a specification.

This invention relates to fixtures particularly designed for use in connection with curtains such as used in the windows of cars and the like. Heretofore curtains of this type have been found objectionable for the reason that, as the car vibrates and sways while in motion, the fixtures which frictionally engage the sides of the window casing tend to creep upwardly so that it is often difficult to maintain the curtain in the position to which it has been lowered.

One of the objects of the present invention is to provide a fixture which is so constructed as to prevent this creeping action.

Another object is to provide a fixture which while operating to hold a curtain securely in any position to which it may be adjusted, will nevertheless yield either upwardly or downwardly so as to permit the curtain to be raised or lowered easily.

Another object is to provide a fixture which can be readily adjusted so that those portions thereof for engaging the window casing will bear against the casing with a sufficient pressure to properly hold the curtain.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of a portion of a curtain in position in a window casing. Fig. 2 is a section on line A—B Fig. 1. Fig. 3 is a view partly in elevation and partly in section of the fixture and the lower portion of the curtain, the rollers being shown in the positions assumed thereby when out of engagement with the casing. Fig. 4 is a front elevation of one end portion of the fixture and showing

the position assumed by the roller while the fixture is being moved upwardly. Fig. 5 is a similar view showing the relative positions of the parts while the curtain is being moved downwardly. Fig. 6 is a plan view of one end of the fixture. Fig. 7 is an enlarged section on line C—D Fig. 6.

Referring to the figures by characters of reference 1 designates a tube engaging the end of the curtain E and having its end portions interiorly screw threaded. Each of these end portions is adjustably engaged by a threaded stem 2 having opposed longitudinally extending flat faces 3 formed with longitudinal grooves 4 in which are secured springs 5 which extend longitudinally of the grooves and diverge outwardly beyond the outer end of the stem as shown at 6. The said stem has a forked head 7 between which the diverging portions 6 of the springs engage and the sides of the fork are connected by a retaining pin 8. A binding nut 9 is mounted on the stem 2 and is adapted to bear against the end of tube 1, while an adjusting nut 10 is mounted on stem and extends over springs 5. By adjusting this nut 10 toward the fork 7, the tension of the springs 5 can be increased, whereas by adjusting it in the opposite direction and toward the nut 9, the tension of the springs can be reduced.

Mounted within the fork 7 is a roller 11 having an enlarged central opening 12 through which the pin 8 extends. The springs 5 bear against the periphery of the roller 11 and, as they exert equal forces upon roller along outwardly converging lines, it will be seen that the roller will be maintained normally in the position shown in Fig. 3 wherein the innermost portion of the wall of opening 12 bears outwardly against the pin 8.

In placing the fixture in position within the window casing F the nuts 9 are loosened and the stems 2 are adjusted so that the distance between the outer extremities of the two rollers embodied in the fixture will be slightly greater than the distance between the inner faces G of the guide grooves H formed in the casing F. Nut 9 is then screwed against the tube 1 so as to bind thereupon and lock the parts against further adjustment. The rollers 11 are then pressed inwardly against the springs 5 so as to permit the insertion of the fixture into the casing after which the rollers are re-

leased and the springs 5 promptly project them into the grooves 8, as shown in Fig. 1. Thus the rollers will bear frictionally against the faces G, the springs 5 serving both to press said rollers against the surfaces G and to hold the rollers against rotation under normal conditions. As hereinbefore stated, the tension of the springs 5 can be controlled by means of the nuts 10.

10 While a car is in motion the sides of the window casing have more or less movement relative to each other and, as before stated, the fixtures heretofore used have thus been caused to creep upwardly so that it is a difficult matter to maintain a curtain in any position to which it may have been adjusted. By providing a fixture such as herein described, however, the rollers 11 will be free to move upwardly, downwardly, rearwardly 20 and outwardly whenever necessary because of the relative movement of the sides of the window casing and, consequently, the creeping action heretofore produced will be eliminated and the curtain will be maintained in any position to which it may be adjusted. The springs 5 further act as cushions so that any jolting of the car body will not result in the fixture creeping upwardly within the casing F. Instead the springs will promptly 30 restore the parts of the fixture to their normal positions relative to each other immediately after any jolting action.

It will be noted, by referring to Figs. 4 and 5 that, when the curtain is pushed upwardly or pulled downwardly, the frictional engagement of the rollers with the sides of the casing is reduced and it is thus possible to move the curtain more readily than would otherwise be the case. For example, when 40 the curtain is pushed upwardly, as shown in Fig. 4, the lower springs 5 will yield downwardly, thus gradually releasing the grip of the rollers upon the casing F and finally allowing the rollers to slide easily in an upward direction within the grooves H. Furthermore, and as shown in Fig. 5, when the curtain is drawn downwardly, the upper springs 5 will yield so as thus to permit the rollers to slide freely within the grooves 50 without producing undesirable friction.

What is claimed is:—

1. In a curtain fixture, the combination with a supporting structure including a retaining pin, of a member mounted on the pin to engage guides on a window frame, said member being mounted to shift radially relative to the pin in any direction, and yielding means carried on the supporting structure and engaging said member for pressing said member outwardly normally against the pin, said yielding means being adapted to resist upward and downward movement of the member relative to the pin.

2. A curtain fixture including a retaining pin, a roller mounted thereon and adapted

to shift diametrically in any direction relative thereto, and yielding means engaging the periphery of the roller for pressing it outwardly normally against the pin, said yielding means being adapted to resist upward, downward and inward movement of the roller relative to the pin. 70

3. A curtain fixture including a forked member, means for connecting the same adjustably to a curtain, a roller mounted to slide diametrically in any direction relative to the forked member, means carried by the forked member for holding the roller against displacement relative thereto, and yielding means engaging the periphery of the roller for projecting it normally outwardly to position, said yielding means being adapted to resist upward, downward and inward sliding movement of the roller. 75 30

4. A curtain fixture including a forked member, means for connecting the same to a curtain, a retaining element carried by said member, a roller mounted to slide diametrically in any direction relative to said element, yielding means engaging the periphery of the roller for holding said roller normally projected to active position, said means being adapted to resist the sliding movement of the roller in any direction out of its normal position, and a device for adjusting said yielding means to vary the pressure exerted thereby upon the roller. 80 90 35

5. A curtain fixture including a forked member, means for adjustably connecting the same to a curtain, a retaining element carried by said member, a roller engaging said element and adapted to slide diametrically in any direction relative thereto, springs engaging the periphery of the roller at two points for holding the roller normally projected to one position and for resisting movement of the roller in any direction from said position. 100 105

6. A curtain fixture including a forked member, means for adjustably connecting the same to a curtain, a retaining element carried by said member, a roller engaging said element and adapted to slide diametrically in any direction relative thereto, springs engaging the periphery of the roller at two points for holding the roller normally projected to one position and for resisting movement of the roller in any direction from said position, and means for varying the tension of the springs. 110 115

7. A curtain fixture including a roller supporting structure, a roller carried thereby and adapted to slide diametrically in any direction relative thereto, springs engaging the periphery of the roller at two points and co-operating to hold the roller normally projected to one position and to resist the sliding movement of the roller in any direction from said position. 120 125

8. A curtain fixture including a support- 130

- ing structure, a roller carried thereby and adapted to slide diametrically in any direction relative thereto, springs engaging the periphery of the roller at two points and coöperating to hold the roller normally projected to one position and to resist the sliding movement of the roller in any direction from said position, and means for varying the tension of the springs.
13. 9. A curtain fixture including a supporting structure, a guide engaging roller carried thereby and adapted to slide diametrically in any direction relative thereto, opposed leaf springs bearing against the periphery of the roller and coöperating to hold the roller normally projected to guide engaging position, said springs being adapted to resist the sliding movement of said roller in any direction away from such position.
10. A curtain fixture including a supporting structure, a guide engaging roller carried thereby and adapted to slide diametrically in any direction relative thereto, opposed leaf springs bearing against the periphery of the roller and coöperating to hold the roller normally projected to guide engaging position, said springs being adapted to resist the sliding movement of said roller in any direction away from such position, and means for varying the tension of the springs.
11. A curtain fixture including a curtain engaging tubular member, a stem adjustably connected thereto, a roller supported by the stem and mounted to slide diametrically in any direction relative thereto, and yielding means engaging the roller for holding it normally projected to active position, said means being adapted to resist the sliding movement of the roller in any direction away from said normal position.
12. A curtain fixture including a tubular curtain engaging member, a stem adjustably connected thereto, a guide engaging roller supported by the stem and slideable diametrically in any direction relative thereto, springs secured to the stem and bearing against the periphery of the roller at spaced points, said springs coöperating to hold the roller normally projected to guide engaging position and to resist the sliding movement of the roller in any direction away from said position.
13. A curtain fixture including a tubular curtain engaging member, a stem adjustably connected thereto, a guide engaging roller supported by the stem and slideable diametrically in any direction relative thereto, springs secured to the stem and bearing against the periphery of the roller at spaced points, said springs coöperating to hold the roller normally projected to guide engaging position and to resist the sliding movement of the roller in any direction away from said position, and means for varying the tension of the springs.

In testimony that I claim the foregoing as my own, I have hereto affixed my signature in the presence of two witnesses.

AUGUST C. RADER.
